FLASHERS AND CIRCUITS THEREFOR
Jesse R. Hollins, Brooklyn, N.Y., assignor to Signal-Stat Corporation, Brooklyn, N.Y., a corporation of New YorkFiled Feb. 24, 1958, Ser. No. 717,050
6 Claims. (Cl. 340—81)

This invention relates to intermittently energized or flashing signal and indicating circuits and, more particularly, to novel circuits of this type including a novel flasher comprising a thermomotive element controlling current flow through parallel load circuits.

In accordance with the invention, a flasher is provided in which the operating elements are enclosed in a sealed envelope which may be evacuated or else filled with an inert gas. This envelope is sealed to a base having three terminals, the usual side terminal and two end terminals. The base may be either a bayonet type, such as used in automotive vehicle lamps, or a screw type.

The envelope contains a high resistance filament supported between a pair of conductors, one connected to a side terminal of the base and the other connected to an end terminal of the base. A thermomotive conductor, such as a bimetallic strip, is connected to the other base terminal and is normally engaged with the filament conductor connected to a base terminal.

In the circuits utilizing the flasher, the side terminal is connected to ground, the filament base end terminal is connected to a load such as grounded signal lamps, and the thermomotive element terminal is connected to a grounded source of potential. Switch means are provided in the circuit leading to such source and in one of the other circuits, the switch means comprising a double pole switch.

When the switch means is closed, current flows from the source through the thermomotive element and then divides between the grounded filament circuit and the grounded load circuit. The filament heats, due to its high electrical resistance, heating the interior of the envelope. This causes heating of the thermomotive element which, upon sufficient heating, deflects to disengage the filament base end terminal conductor. The filament and load circuits are thus opened, and the filament cools. After sufficient cooling, the thermomotive element re-engages the filament conductor to re-close the filament and load circuits, and the cycle repeats.

For an understanding of the invention principles, reference is made to the following description of typical embodiments thereof as illustrated in the accompanying drawings. In the drawings:

FIGS. 1 and 2 are schematic wiring diagrams of an automotive vehicle turn signal system embodying the invention, respectively illustrating the circuit closed and circuit open conditions; and

FIGS. 3 and 4 are corresponding schematic wiring diagrams of an automotive vehicle turn signal system embodying a preferred circuit arrangement of the invention.

The circuits shown in each of the four figures include a flasher 10 comprising a sealed envelope 11 sealed to a base 12. Envelope 11 may be evacuated or may be filled with an inert gas. Base 10 includes the usual side terminal 13 and central terminals 14 and 16. Envelope 11 contains a high resistance filament 15 mounted on a conductor 17, connected to contact 13, and a conductor 18, connected to contact 14. A conductor 21, connects terminal 16 to the fixed end of a bowed thermomotive element 20 having a free end normally engaging conductor 18.

For illustrative purpose, base 12 is shown as a bayonet

type engaged in a bayonet type socket 25 including a conductive metal side wall 22 engaging base 12 (terminal 13) and spring biased contacts 24, 26 respectively engaging base end terminals 14 and 16. Contacts 24, 26 are insulated from base 25 in the manner customary with automotive vehicle lamp sockets, and are connected to conductors 27, 28, respectively. Base side wall 22 is connected to a conductor 23.

In the turn signal circuit of FIGS. 1 and 2, conductors 23 and 27 are connected to the movable arms 31, 32 of a double pole, double throw turn signal switch 30, and conductor 28 is connected to the live terminal 36 of a grounded battery 35 representative of the electric potential source of an automotive vehicle.

Switch arm 31 is adapted to engage either of a pair of contacts 33, 33 which, in FIGS. 1 and 2, are grounded. Switch arm 32 is arranged to engage a contact 34L or a contact 34R. Contact 34L is connected to grounded left turn signal lamps LF and LR, and contact 34R is connected to right turn signal lamps RF and RR.

In the turn signal arrangement of FIGS. 3 and 4, conductor 23 is connected directly to ground and conductors 28 and 27 are connected to switch arms 31 and 32, respectively. Contacts 33 are connected to live terminal 36 of battery 35 and contacts 34L and 34R are connected in the same manner as in FIGS. 1 and 2.

In the system of FIGS. 1 and 2, when switch 30 is operated to signal a right turn, for example, an arm 31 engages a grounded contact 33 and arm 32 engages contact 34R. Current flows from battery 35 through terminal 36, conductor 28, contacts 26 and 16, element 20, and conductors 18 and 27. The current then flows through a pair of parallel circuits. One circuit comprises conductor 18, filament 15, conductor 17, conductor 23, arm 31, contacts 33 and ground. The other circuit comprises conductor 18, contacts 14 and 24, conductor 27, arm 32, contact 34R, and lamps RF and RR in parallel to ground.

As filament 15 heats the interior of envelope 11, element 20 heats and deflects away from conductor 18 as shown in FIG. 2. Current ceases to flow in both the parallel load circuits, and lamps RF and RR and filament 15 are extinguished. As filament 15 cools, element 20 cools and reengages conductor 18. The cycle then repeats.

The preferred arrangement of FIGS. 3 and 4 operates in an equivalent manner. In this arrangement, base 25 is always grounded and battery 35 is connected to element 20 only when switch 30 is moved from neutral to either operated position. An arrangement of this type is preferable to that of FIGS. 1 and 2 for safety reasons due to the unbroken ground circuit of socket 25.

In both embodiments, known pilot lamp arrangements may be used, as well as the pilot lamp operators of my copending application Serial No. 716,649, filed February 21, 1958, issued as Patent No. 2,942,236 on June 21, 1960, and my copending application Serial No. 717,164, filed February 24, 1958, and issued December 29, 1959, as Patent No. 2,919,424.

While specific embodiments of the invention have been shown and described in detail to illustrate the application of the invention principles, it will be understood that the invention may be embodied otherwise without departing from such principles.

What is claimed is:

1. A thermostatic circuit interrupter or flasher comprising, in combination, a sealed envelope; a base sealed to said envelope and having three terminals; a high resistance filament in said envelope; a pair of conductors projecting substantially from said base into said envelope and each having one end connected to a pair of base ter-

minals, the opposite ends of said conductors being connected to opposite ends of said filament; and a thermomotive element extending from said base into said envelope between said conductors and connected to the third terminal, the free end of said element being normally engaged with an intermediate portion of one filament conductor within said envelope; said element, when heated due to heating of the interior of the envelope by said filament when current flows through the latter, disengaging said one filament conductor.

2. A thermostatic circuit interrupter or flasher comprising, in combination, a sealed envelope; a base sealed to said envelope and having three terminals; a high resistance filament in said envelope; a pair of conductors projecting substantially from said base into said envelope and each having one end connected to a pair of base terminals, the opposite ends of said conductors being connected to opposite ends of said filament; and a thermomotive element extending from said base into said envelope between said conductors and connected to the third terminal, the free end of said element being normally engaged with an intermediate portion of one filament conductor within said envelope; said element, when heated due to heating of the interior of the envelope by said filament when current flows through the latter, disengaging said one filament conductor; said element being included in the energizing circuit of said filament whereby, upon said disengagement, said filament will cool and said element will re-engage said filament conductor.

3. An intermittently energized electrical system comprising, in combination, a thermostatic flasher including a sealed envelope, a base sealed to said envelope and having three terminals, a high resistance filament in said envelope, a pair of conductors projecting substantially from said base into said envelope and each having one end connected to a pair of base terminals, the opposite ends of said conductors being connected to opposite ends of said filament and a thermomotive element extending from said base into said envelope between said conductors and connected to the third terminal, the free end of said element being normally engaged with an intermediate portion of one filament conductor within said envelope, said element, when heated due to heating of the interior of the envelope by said filament when current flows through the latter, disengaging said one filament conductor; a source of potential; a first load circuit connected to one of said pair of terminals; a second load circuit connected to the other of said pair of terminals; a supply circuit connected to said source and to said third terminal; and normally open conjointly operable switch means in said supply circuit and one load circuit controlling the simultaneous connection of said supply circuit and said one load circuit to their respective terminals.

5. A system as claimed in claim 3 in which one of said load circuits is directly grounded and the other load circuit comprises a grounded lamp load.

6. A system as claimed in claim 3 in which said switch means comprises a double pole selector switch having a neutral position and a pair of operated positions; one pole of said selector switch, in either operated position, connecting one circuit to its terminal; the other pole of said selector switch being connected to the respective terminal of its circuit and being selectively engageable with either of a pair of contacts; and sets of turn signal lamp means, each being connected to one of said contacts.
